COMPACT

Paul H. Ganz, New York, N. Y.

Application July 13, 1935, Serial No. 31,170

5 Claims. (Cl. 132—82)

This invention relates to a compact or the like, adapted to contain powder, cosmetics and similar substances.

Among the objects of my invention are the provision in a compact of closure means for conveniently opening and closing the compact, the provision of closure means that will be effective against loss of the contents or the aroma thereof, and the provision of closure means distributed in relation to the parts to be held together instead of being concentrated in a restricted zone in the customary way, whereby the danger of opening at improper times is minimized, and the provision of closure means flexibly supported in relation to the compact.

I attain these objects by providing a compact with a cover having parts thereof interfitting with the parts of the body so that the contacting surfaces of cover and body are of ample area and the provision in connection with such surfaces of a slide fastener, parts of which are flexibly carried from the cover and the bottom, and extend along the contacting portions thereof, and are adapted to hold the said interengaging surfaces in the closure position, and which form, in conjunction with the aforementioned interfitting surfaces of cover and body, a double barrier, preventing escape of the contents and its aroma when the compact is closed.

For the attainment of these objects and such other objects as will hereinafter appear or be pointed out I have illustrated an embodiment of my invention in the drawing, in which:

Figure 1 is a plan view of a compact constructed according to my invention;

Figure 2 is a side elevation of the same, viewed from the left of Figure 1;

Figure 3 is a side elevation of the same viewed from the right of Figure 1;

Figure 4 is a cross sectional view on the line 4—4 of Figure 1; and

Figure 5 is a perspective view showing the cover in its open position and with the interior and the contents thereof exposed to view.

Referring to the drawing in detail it will be observed that my compact comprises a body member having a bottom 10 and a rim 12 upstanding therefrom so as to form a hollow adapted to receive material to be carried by the compact, such as the powder indicated at 14. The rim 12 may be made of rigid material so as to be form-retaining, and is shown in the illustrative embodiment as circular in external contour and circular in internal contour except at the back 55 where the rim is widened as shown at 13, so that

the hollow interior has a contour that is circular but with a segment at the back filled in. The cover member 16 is hinged at 18 to the edge of the widened portion 13 of the rim, and is contoured so as to conform to the outlines of the bottom portion. A mirror 20 is shown as carried by the inside surface of the cover member 16 and this mirror is circular in shape, except that a segment of the circle is removed at the back thereof. The mirror is further made of such size that it will fit closely within the space bounded by the inner portion of the rim whereby it will serve to keep the cover in alignment with the bottom when the cover is in closed position and its outer edges will provide additional surfaces at the juncture of the cover and the bottom, cooperating with the upper edge of the rim and the surfaces on the cover contacting therewith, for more effectively preventing escape of the contents and of the aroma thereof. It will be observed that in this arrangement, as illustrated, the two sets of cooperating surfaces are angularly related to each other, and this angular break, by destroying the directness of the path of escape of the contents of the compact, where such a path exists because of poor interfitting between the cover and body members, is more efficient in preventing such escape than a continuous flat surface of the same area would be.

In order to hold the cover in closed position I provide a closure of the slide fastener type arranged, with one of the interlocking jaw members 22 thereof fastened to the periphery of the cover member 16, and the other interlocking jaw member 24 thereof fastened to the periphery of the base member. The interlocking members, as shown in the drawing, are flexible, and they are of such width that when interlocking is effected by the closure member 26, the cover and the body will be closely held together, with portions of the surfaces thereof in close contact and with the outer edges of the mirror in close adjacency to the inner surface of the rim of the body member. The slide fastener thereby forms in effect an outer wall and the rim and the cover portions covered thereby form an inner wall, and the double walled construction in the region of closure is of great advantage in retaining the contents and preserving it in suitable condition. The flexibility of the fastener parts on the other hand, coupled with this elasticity, which accompanies their flexibility to a greater or lower degree, makes for convenience in manipulation and efficiency of closure.

- The portions 22 and 24 of the slide fastener are extended at one side in back of the hinge member 18, so that the closure member 26 may slide beyond the hinge 18 and when in such position the 5 cover will be free to rise from the case. At the other end of the slide fastener such extension is not necessary, although, if desired, the slide fastener at this point may also be extended in back of the hinge 18.
- 10 10 The interior of the compact may be arranged in any preferred manner. For example over the powder there may be arranged a sifter 28 to hold the powder 14 in place and yet permit its 15 passage therethrough, and above the sifter may be kept a powder puff 30.

15 It will further be understood that for the purposes of making a commercially attractive article that the entire case may be appropriately covered with attractive material and that other 20 ornamental touches may be added to the same as desired.

25 While I have shown one embodiment of my invention it will be understood that the same may be embodied in many other forms, as will be obvious to those skilled in the art, and that the disclosure herein is to be interpreted as illustrative merely and in no sense limiting, and that I do not limit myself in any way other than as defined in the appended claims.

30 Having thus described my invention and illustrated its use, what I now claim and desire to secure by Letters Patent, is:—

35 1. A compact comprising a hollow body member having relatively rigid upstanding side walls, a relatively rigid cover member hingedly carried by said body member and adapted to cooperate with portions of said side walls so as to close the compact, a flexible flap member carried by said body member and surrounding said side 40 walls, a second flexible flap member complementary to said first-mentioned flexible flap member, fastened and depending from the cover member and adapted to surround said side walls when said cover member is in place, and said 45 flexible flap members having their free edges formed with interfitting portions, and a closure member adapted to effect engagement of said interfitting portions when moved in one direction and disengagement when moved in the opposite 50 direction, whereby said flap flexible members will serve to lock said cover member in closed position or to permit the case member to open, said flap members being so proportioned that they lie in relative adjacency to the side walls of said 55 body member, thereby in effect constituting a flexible outer wall superimposed on the side walls of the body member, and said interfitting portions of said flexible flap members being positioned out of registration with the said cooperating closure portions of said body member and said cover member.

60 2. A compact comprising a hollow body member having relatively rigid upstanding side walls, a relatively rigid cover member hingedly carried by said body member by a hinge spaced from the edge thereof and adapted to cooperate with portions of said side walls so as to close the compact,

65 a flexible flap member carried by said body member and surrounding said side walls in the region where they engage the side walls, a second flexible flap member complementary to said first mentioned flexible flap member, fastened to the cover member and adapted to surround said side walls when said cover member is in place, and said flexible flap members having their free edges formed with interfitting portions, and a closure member adapted to effect engagement of said interfitting portions when moved in one direction and disengagement when moved in the opposite direction, whereby said flexible members will serve to lock said cover member in closed position or to permit the case member to open said 10 flap members being so proportioned that they lie in relative adjacency to the side walls of said body member, thereby in effect constituting a flexible outer wall superimposed on the side walls of the body member, and said interfitting portions of said flexible flap members being positioned out of registration with the said cooperating closure portions of said body member and said cover member, and said flexible closure extending along said walls beyond said hinge member, at one end 15 thereof.

3. In a compact a relatively rigid hollow body member, and a relatively rigid cover member hingedly associated with said body member, and adapted to form in conjunction therewith a closed 20 compartment, said body and cover members having portions thereof adapted to interfit when the compact is closed, and closure means in the form of flexible walls associated with said body and cover members, external to said interfitting portions, said closure means also having portions adapted to interfit when the compact is closed, and said interfitting portions of said external closure means being out of registration with the interfitting portions of said body and cover members, and thereby forming an outer wall adapted to 25 cooperate with the walls of the body and cover to prevent the escape of and to preserve the contents of the compact.

4. In a compact a hollow body member and a 30 cover member hingedly associated with said body member, said body and cover members having portions thereof adapted to interfit when the compact is closed, and closure means in the form of a flexible wall associated with said body and 35 cover members, external to said interfitting portions, said closure means also having portions adapted to interfit when the compact is closed, and thereby forming an outer wall adapted to 40 cooperate with the walls of the body and cover to 45 prevent the escape of and to preserve the contents of the compact, and said external closure means being flexibly carried by said body and cover members.

5. A compact having a body member and a 50 cover hinged thereto, and having complementary portions adapted to engage and thereby to close the compact, and flexible walls external to and adjacent said complementary portions, said flexible walls being provided with locking means for 55 keeping the compact closed.

PAUL H. GANZ.
